UNITED STATES PATENT OFFICE.

DAVID W. DUNLEVY, OF PITTSBURGH, PENNSYLVANIA, ASSIGNOR TO COLONIAL STEEL COMPANY, OF PITTSBURGH, PENNSYLVANIA, A CORPORATION OF PENNSYLVANIA.

APPARATUS FOR CLEANING HOLLOW METAL RODS.

1,231,579.

Specification of Letters Patent.

Patented July 3, 1917.

Application filed July 22, 1916. Serial No. 110,679.

To all whom it may concern:

Be it known that I, DAVID W. DUNLEVY, a citizen of the United States, and resident of Pittsburgh, in the county of Allegheny and 5 State of Pennsylvania, have invented a new and useful Improvement in Apparatus for Cleaning Hollow Metal Rods; and I do hereby declare the following to be a full, clear, and exact description thereof.

10 My invention relates to the cleaning of hollow metal rods, bars, and the like, from the sand or other refractory material in the core, around which the bars are formed. One method of forming hollow metal bars is 15 by drilling a central hole in the bloom or billet; filling the same with sand or other refractory material; closing the ends thereof; and heating and rolling out the bar to finished form. Such bars are used for hollow 20 drill steel, or for other suitable purposes.

The object of the invention is to provide means for removing the sand or like core from the bar so formed. It consists, generally stated, in a hollow support for the 25 tube to be cleansed, feed-rolls mounted in line with the tube, a cylinder in line with said feed-rolls, an inner telescoping tube within the cylinder and engaging the feed-rolls and entering the tube to be cleansed, 30 and a reservoir for water under pressure 20 communicating with the cylinder. It also comprises certain other improvements as 35 hereinafter more particularly set forth and claimed.

35 In the accompanying drawing, Figure 1 is a side view of the apparatus embodying the invention; Fig. 2 is a top or plan view thereof; Fig. 3 is an enlarged longitudinal section of the main operating parts; Fig. 4 is a 40 view of the feed-rolls; and Fig. 5 is a longitudinal section of the bar or tube to be cleansed, showing the telescoping tube operating therein.

The tube or bar 1 to be cleansed rests on 45 suitable standards 2 in line with the hollow support 3, its end being secured to the support by passing through a suitable lined bushing 4 being rigidly secured therein by means of a clamping bolt 5. The support 50 has leading therefrom a suitable drain 6 for carrying off the refractory material of the core washed from the tube, and the water used for such washing operation. In line with the bushing 4 are the feed-rolls 7, which 55 are shown as hand-driven and which may

be power-driven in any suitable manner, there being two of such feed-rolls mounted in a suitable frame 8 secured to the hollow support 3, and the roll trunnions carrying the pinions 9, which mesh with each other, so that through the handle 10 the telescoping tube 11 may be gradually fed through the rod or tube 1 to be cleansed, as hereinafter described. The feed-rolls 7 are grooved as at 12, two of such grooves are shown, adapting the rolls to be used with different sizes of telescoping tubes. These rolls engage with the telescoping tube 11 to feed it forward at the desired speed or withdraw it from the hollow bar or tube after the 70 cleansing thereof. In cleaning the larger sizes of rods the largest groove of the rolls is employed, the roll frame being adjustably secured to the support 3 by slot-and-bolt connection is shifted to bring the pass into 75 register with the bushing 4. A larger tube 11 and stuffing is substituted for the smaller and the liner 4^a removed from the bushing 4. This inner telescoping tube 11 is mounted in the long cylinder 13 supported in suitable 80 standards 14, and having at its rear end the valve 15 communicating with the water reservoir 16. The reservoir communicates with any suitable source of water-supply under high pressure, which is not shown. For the 85 convenience of the operator, the valve 15 is operated by the hand-lever 17 through suitable connecting-rods 18, said hand-lever being located in convenient position for the workman. The cylinder 13 and the inner 90 telescoping tube 11 are of any suitable length according to the rods or bars to be operated upon. The inner telescoping tube is preferably made of light steel tubing somewhat smaller than the bore of the hollow 95 rod or tube to be cleansed, and it is mounted loosely in the cylinder 13, passing through a stuffing-box 19 at the end of the cylinder. It is preferred that the inner tube 11 shall have its inclosed end enlarged or flared 100 somewhat, as at 20, so that the tube will be fed forward by the pressure developed within the cylinder, though this is not a necessity. An abutment 21 is preferably employed beyond the standards 2 for the hollow 105 rod to be cleansed, so that in case the clamping bolt slips the movement of the tube operated upon will be checked after it escapes from its clamping-bushing 4.

In the use of the apparatus, the hollow 110

rod or tube 1 to be operated upon has its solid ends cut or broken off, exposing the inner sand core 22 (see Fig. 5). The hollow rod is then placed on the standards 2 and secured within the clamping-bushing 4 and the inner tube 11 is fed by the feed-rolls 7 across the hollow support 3 and entered into the hollow rod or tube, and by the operation of the valve 15, the water under high pressure is admitted to the cylinder 13; and as the inner tube 11 is gradually fed forward, this water under high pressure impinges upon the sand or other refractory material, the refractory material and water escaping from the hollow rod into the receptacle 3 and thence through the drain 6. The inner tube 11 is thus gradually fed forward while the refractory core is being washed out and until the tube passes entirely through the hollow rod or tube; the inner tube being preferably maintained close to the sand core to be operated upon so that the full force of the stream of water under pressure operates upon and washes out the same. If the hollow rod to be cleansed is of too great length, it may be washed out for part of its length and then reversed and the remainder of the core then washed out. When the core is thus broken through, the stream of water escaping through the hollow rod will wash out any remaining portion of the sand or other refractory material.

The feeding of the inner tube 11 through the cylinder 13 may be aided or accomplished by the enlarged inner end 20 of the inner tube traveling within the cylinder. However, it is necessary to have the feed-rollers for the withdrawal of the telescoping tube after the operation is completed, and such feeding through the pressure of the water and within the cylinder is not entirely depended upon.

The operation is rapid, and while high pressures of liquid are employed, the tube is thoroughly cleansed by the water flowing backwardly around the inner tube 11 entering the hollow rod, and as the refractory material is thoroughly moistened or wetted

in the process of removal, the objectionable feature of such refractory material carried in any escaping atmosphere is overcome.

What I claim is:

1. In apparatus for cleansing tubing, the combination of a hollow support for a tube to be cleansed, feed-rolls mounted in line with the tube, a cylinder in line with said feed-rolls, an inner tube telescoping within the cylinder and engaging the feed-rolls and adapted to enter the tube to be cleansed, and a reservoir for water under pressure communicating with the cylinder. 60

2. In apparatus for cleansing tubing, the combination of a hollow support for the tube to be cleansed, a cylinder in line with said support, an inner tube telescoping within the cylinder and adapted to enter the tube to be cleansed, and a reservoir for water under pressure communicating with the cylinder. 65

3. In apparatus for cleansing tubing, the combination of a hollow support for a tube to be cleansed, a cylinder in line with said support, an inner tube telescoping within the cylinder and engaging the feed-rolls and adapted to enter the tube to be cleansed, a reservoir for water under pressure communicating with the cylinder, the inner tube having an enlarged end traveling within the cylinder. 70

4. In apparatus for cleansing hollow rods or tubes, the combination of a hollow support for the tube to be cleansed, a clamping-bushing for connecting the tube with said hollow support, standards for supporting the hollow rod, a tube adapted to enter the bore of the hollow rod and cleanse the refractory core therefrom, and an abutment in line with the hollow rod when supported on the standards. 80

In testimony whereof, I the said DAVID W. DUNLEVY, have hereunto set my hand.

DAVID W. DUNLEVY.
